UNITED STATES PATENT OFFICE.

HYMAN DIENER, OF WASHINGTON, DISTRICT OF COLUMBIA, ASSIGNOR TO UNITED STATES HOFFMAN MACHINERY CORPORATION, OF NEW YORK, N. Y., A CORPORATION OF DELAWARE.

COMBINATION BACKPLATE AND PLAITING ATTACHMENT FOR PRESSING MACHINES.

Application filed November 4, 1926. Serial No. 146,206.

My invention relates to new and useful improvements in garment pressing machines and more particularly to certain accessories therefor necessary to the completion of an effectively operating pressing machine.

The primary object of the invention resides in providing a combined back plate and plaiting attachment for the machine, the attachment being so incorporated in the plate as to be free from the pressing buck and substantially out of the view of the operator and observer, when said attachment is not in use.

A further object of the invention resides in providing a back plate of the usual type applied to the bed or table of a pressing machine having means incorporated therein and thereon adapted for movement across the working face of the lower pressing element of a machine for holding the work on said element.

A still further object of the invention resides in combining with the back plate of a pressing machine, an attachment including a tape adapted to be drawn across the lower pressing element of the machine and yieldingly engage with the table or bed of said machine, together with means for automatically withdrawing said tape to the back plate when said tape is released from engagement to the table or bed of the machine.

Still another object resides in providing on the back plate a plurality of compartments in which the work-holding tapes are supported, the construction thereof being such as to receive and substantially hide from view said tapes when the latter are not in use.

A still further object resides in providing an attachment in connection with the back plate of a pressing machine which includes a plurality of spring-held tapes which are adapted to be drawn across the lower pressing element of the machine to hold plaits in position when a plaited garment is being pressed, said tapes being adapted to be automatically returned to an inoperative position wholly to one side of said pressing member and substantially out of view, when said tapes are released from the other side of said pressing member.

With these and numerous other objects in view, my invention consists in the novel features of construction, combination and

arrangement of parts as will be hereinafter referred to and more particularly pointed out in the specification and claims.

In the accompanying drawing, forming a part of this application,

Figure 1 is a plan view of a garment pressing machine, with the upper buck or pressing member and its operating structure removed, having my improvements incorporated therein.

Figure 2 is a front elevation thereof, with parts in section, the plait-holding tapes being disclosed in their inoperative positions in the compartments of the back plate of the machine, and

Figure 3 is a vertical transverse section through the device as seen on the line 3—3 of Figure 1, with the tapes in their inoperative positions and showing in dotted lines the operative positions of said tapes.

In describing the invention I shall refer to the drawing in which similar reference characters designate corresponding parts throughout the several views and in which 1 designates the table or bed of the usual garment pressing machine having mounted thereon in the usual or in any preferred manner the lower buck 2, the upper buck or pressing member 3 being shown in dotted lines in Figure 3 of the drawing.

In substantially all up-to-date garment pressing machines of the type herein disclosed, there is provided a back plate to prevent the garments from contacting with the operating structure in the rear of the table and for other obvious reasons. My invention contemplates the provision of such a back plate but constructed to cooperate with a plaiting attachment, as will be hereinafter and more particularly described.

To this end I provide a back plate 4 which is removably secured to the rear edge of the table 1 and generally constructed as usual. This plate at predetermined portions therein is provided with a plurality of vertical, spaced-apart slots 5, which are relatively wide. Secured to the rear face of the plate 4 to enclose each of said slots 5 is a box-like casing 6, which is substantially triangular in side elevation. These casings may be made in other designs, if desired, and of various materials, but are preferably constructed of metal, the end edges of the walls thereof being bent outwardly to form flanges

7, through the medium of which said casings may be removably secured to the plate 4.

Rearwardly projecting compartments are thus formed on the back plate 4, the entrance to said compartments being through the medium of slots 5. An inverted U-shaped strap 8 applied to the top and side walls of each casing 6 forms a bracket or bearing for a pintle 9 extending transversely through the side walls of the casing upon which pintle is rotatably mounted a spring reel 10. This reel has wound thereon a tape 11 formed of any desired material such as a woven band adapted to be drawn through the opening or slot 5 in the plate 4, the tape being guided between a pair of slightly spaced and vertically alining rollers 12' which are supported between the side walls of the casing 6 forward of the spring reel.

20 Various forms of spring reels or spring rollers may be used and other means than that illustrated and described may be utilized for retaining the spring reels or rollers in position. As many spring reels and corresponding tapes may be used as desired, it being essential to have sufficient number to retain the plaits of a plaited garment in position while said garment is being pressed.

As appears obvious the tapes are adapted 30 to be drawn across the buck 2 to hold the garment in position on the latter and the outer ends of said tapes engaged with elements on the opposite side of said buck. In carrying out this idea, I prefer to provide

35 a plurality of small coil spring members 12 which are secured to the outer ends of the tapes 11 which will permit a reasonable and, more or less, necessary resiliency of the tapes when they are secured in position and to

40 the outer ends of the coil spring members are loosely engaged hook members 13 formed with finger pieces 14 intermediate their ends. The hooks 13 are adapted for engagement with the loosely mounted and vertically mov-

45 able clips 15 mounted with openings in the table 1 adjacent the front edge of the support for the buck 2, as clearly shown in the drawing. The upper face of the table 1 is recessed as shown at 16 at the points where

50 the clips 15 are mounted, which enables the crowns of said clips to be normally below the surface of said table and permits the fingers of the operator to readily raise said clips to be engaged by the hooks 13.

55 It will thus be seen that the spring-held tapes may be readily drawn across the buck to hold the plaited garment in position and the hooks at the ends of said tapes removably engaged with the clips in the table forward of the buck. When the operator completes his work with the plaiting attachment, each of the hooks 13 on the tapes 11 may be

60 manually disengaged from the clips 15 and release thereof will permit the tapes to be 65 reeled automatically within the casings 6, the

same being guided through the slots 5 and the rollers 12'. Obviously, the tapes are drawn wholly to one side of the buck and free from engagement or interference with the operator and his work. To further free the machine of an interference with this attachment and to give a neat appearance when the attachment is in its inoperative position, I construct the parts in such a manner with respect to the slots 5 in the back plate that the hooks 13 may be tucked within the slots and hidden therebelow in the compartments formed by the casings 6, as shown in Figure 3 of the drawing. Thus, there appears to be no projecting portions on the device and the back plate appears clear of the attachment. The attachment is, therefore, substantially hidden from view when the tapes are in their inoperative positions but ready for easy manipulation when desired.

The spring reels 10 return the tapes to their inoperative positions when the latter are released from engagement with the clips 15 and the coil springs 12 provide the necessary resiliency to take care of materials of varying thicknesses and adjustments that may be made as the operator draws the tapes to position. While the springs 12 are not essential their presence is advantageous in that they tend to relieve the springs of the reels from undue strain and likewise tend to equalize the pull on the tapes thus preventing any drag or draw of the tapes on the goods.

From the foregoing it will be seen that I have provided a simple, inexpensive and efficient means for carrying out the various objects of the invention and while I have particularly described the elements best adapted to perform the functions set forth, it is obvious that various changes in form, proportion and in the minor details of construction may be resorted to, without departing from the spirit or sacrificing any of the principles of the invention.

Having described my invention what is claimed is:

1. In a pressing machine, the combination with a table and pressing element thereon; of a back plate carried on said table and extensible means supported on the rear of said plate and adapted for cooperation with said pressing element to retain garments in position on the latter at predetermined times.

2. In a pressing machine, the combination with a table and pressing element thereon; of a back plate mounted on said table and extensible means supported at the rear of said plate in line with openings formed therein and adapted for cooperation with the pressing element to retain garments in position on the latter.

3. In a pressing machine, a buck, a back plate, extensible members supported thereon

and cooperating with the buck to position a garment on the latter and means cooperative with said plate and members to hide the latter from view when the same are in inoperative position.

4. An attachment for garment pressing machines including a buck and a back plate, compartments carried on the rear face of the plate in line with openings formed in said plate, spring actuated reels mounted respectively in said compartments, tapes engaged at their one end respectively with said reels, said reels tending to normally draw said tapes wholly within said compartments and means for releasably engaging the opposite ends of said tapes when the latter are drawn over the buck.

5. In a pressing machine of the class de-

scribed, the combination with a table, and a pressing element, thereon; of a back plate 20 mounted on said table, said plate having openings formed at predetermined points therein, compartments mounted on the rear face of said plate in line with said openings, spring actuated reels mounted in said compartments, tapes engaged at their one end respectively with said reels and adapted to be drawn through the openings in said plate, 25 said reels tending to normally draw said tapes to inoperative position wholly within 30 said compartments, and means forward of the pressing member for releasably engaging the other ends of said tapes when the latter are drawn across said pressing member.

In testimony whereof I affix my signature.

HYMAN DIENER.
